[57] CLAIM

The ornamental design for a beverage dispenser valve, as shown and described.

DESCRIPTION

FIG. 1 is a top, front, left side perspective view of a beverage dispenser valve showing my new design;
FIG. 2 is a left side elevational view thereof;
FIG. 3 is a front elevational view thereof;
FIG. 4 is a rear elevational view thereof;
FIG. 5 is a top plan view thereof;
FIG. 6 is a right side elevational view thereof; and
FIG. 7 is a bottom plan view thereof.
FIG. 8 is a top, front, left side perspective view of a modified form of my new design;
FIG. 9 is a left side elevational view thereof;
FIG. 10 is a front elevational view thereof;
FIG. 11 is a rear elevational view thereof;
FIG. 12 is a top plan view thereof;
FIG. 13 is a right side elevational view thereof; and
FIG. 14 is a bottom plan view thereof.
